CYLINDER CONSTRUCTION

Henry E. Muchnic, Atchison, Kans., assignor to
 The Locomotive Finished Material Company,
 Atchison, Kans., a corporation of Kansas

Application January 24, 1934, Serial No. 708,080

7 Claims. (Cl. 105—44)

My invention relates to a locomotive cylinder structure preferably cast in a single piece and of such construction as to eliminate the serious objections resulting from unequal expansion encountered by different portions of the unit.

It has been found extremely difficult and less practical to cast the steam passages entirely free or dissociated from the walls of the main casting, as the steam passages or conduits, in order to be entirely separate from the front and rear vertical walls of the main casting, would have to be given a curvature which would necessitate adding to the length of the steam chests beyond the limiting restrictions or dimensions of a locomotive cylinder.

It was also found that in casting the steam conduits entirely free of the main casting and remain within the limiting dimensions prescribed it would impose restrictive curves in the steam passages.

My present invention is designed to overcome these difficulties and at the same time it solves the difficulty encountered by the alternate expansion and contraction of steam passages cast integral with the front and the back walls and does so in a more practical and economical way than in the structure heretofore designed and as disclosed in my pending application Serial No. 553,276; the structure providing steam passages independent, generally, of the walls of the casting, which are free to expand without affecting or straining the walls of the cylinder casting.

My invention also involves a construction wherein the cylinder portions are more securely and rigidly attached to the main structure by means of a grid arrangement of ribs or webs, thus affording a structure which will be free of the serious difficulties heretofore encountered in cylinder constructions which have resulted in failures where the cylinder proper joins or attaches to the main structure, due to the fact that the alternate stresses in the cylinders, when the locomotive is in operation, are concentrated at the frame fit. In my improved cylinder construction this part of the structure has been greatly strengthened without the addition of material or undue weight.

The various objects and advantages of my invention will all be readily comprehended from the following detailed description of the accompanying drawings, wherein:

Figure 1 is a partial plan and longitudinal sectional view of one side or half of a locomotive cylinder construction involving my invention.

Figure 2 is a detail sectional view taken sub-

stantially on the line 2—2 of Figure 1 as viewed by the arrows and illustrating a part of my invention.

Figure 3 is a partial elevation and vertical section with a portion of one cylinder broken away; the section being taken substantially on the line 3—3 of Figure 1, looking in the direction of the arrows.

My invention relates to a steam locomotive cylinder construction preferably of cast steel wherein the exhaust steam passages or conduits throughout the major portions are independent of the walls of the casting; portions, however, having web connections with the outer wall portions of the casting. That is to say, the improved cylinder construction as exemplified in the drawings, discloses the exhaust conduits, preferably at the tops and bottoms connected with the outer walls of the main casting thus giving the partially connected conduits the freedom desired to compensate for differences in degrees of expansion and contraction and thus obviating the difficulties encountered wherein the steam passages constituted a structural wall of the casting proper; while at the same time eliminating the difficulties encountered in the casting of a structure wherein the exhaust steam passages were entirely dissociated from the outer walls of the structure.

The embodiment of the invention, as illustrated in the drawings, involves the valve chambers 10, 10 at opposite ends or sides of the structure, and the cylinders 11, 11 provided with the usual steam passages or ports between the respective valve chambers and cylinders but not shown; the chambers and cylinders being integrally united in a single casting.

The casting is of more or less skeleton formation; the oppositely located valve chambers and cylinders being united by means of a top wall 12, a bottom wall 13 and the front and rear walls 14 and 15. The top, bottom, front and rear walls are reenforced and united by the vertically disposed webs 16, 16.

The top wall merges into the saddle portion 17 whereby the casting is secured to the boiler shell of a locomotive by means of bolts.

The front and rear walls 14 and 15 at opposite ends and intermediate of the valve chambers 10 and the adjacent vertically disposed webs are each provided with the openings 18; while the vertical webs 16 are each provided with an enlarged opening 19. These openings are provided for the passage of the exhaust steam conduits 20, 20, which lead from and are formed integral

with opposite ends of the two valve chambers or steam chests 10, 10. These conduits extend substantially parallel with the front and rear walls, respectively, of the casting until they reach the 5 openings 18, curving inwardly through these openings 18, then curving toward the webs 16 and passing through the openings 19 therein; the two exhaust conduits 20 from opposite ends of the chamber then uniting in an upwardly disposed 10 discharge end 21, which extends through an opening in the saddle portion 17 of the casting.

The discharge ends 21, 21 of the conduits leading from the two valve chambers are shown formed integral with a transversely disposed web 15 22 formed integral with the front and rear walls of the casting. The united discharge ends 21, 21 are shown provided with an exhaust nozzle receiving flange 23.

The upwardly disposed ends 21 of the two pair 20 of conduits are reenforced by the vertical pedestal portion or skeleton wall 24.

Heretofore, locomotive cylinders have been made of cast steel but involved serious problems because of the increased linear expansion of cast 25 steel over cast iron and the frequent cracking and breaking of the casting, resulting from the fact that the exhaust steam passages constituted a structural portion of the casting proper.

In order to overcome this difficulty it has been 30 proposed to entirely dissociate the exhaust steam passages or conduits from the walls of the casting, as for example in the manner disclosed in my application Serial No. 553,276. It was, however, found to be practically impossible to cast a locomotive cylinder structure with the exhaust steam 35 conduits entirely dissociated or completely free from the front and rear walls of the main structure without providing the exhaust passages or conduits with restrictive curves.

40 My invention, as disclosed in the drawings, contemplates a cylinder construction or casting wherein the exhaust passages or conduits 20 have a partial or web connection with the outer walls of the casting as shown for example at 25.

45 The web connections are merely made with the tops and bottoms of the exhaust conduits, thus leaving the vertical sides of the conduits or passages entirely free or disconnected from the outer casting. This permits the exhaust passages 50 to keep within the limiting dimensions of a locomotive cylinder, without imposing restrictive curves in the exhaust passages; while at the same time incorporating all the advantages of an entirely dissociated steam conduit and solving, in 55 a more practical and economical manner, the difficulties encountered by the alternate expansion and contraction of steam passages cast integral with the front and rear walls of the main casting. As is apparent from the drawings, the 60 large vertical side walls of the exhaust passages 20 are entirely free, while the web connections 25, 25 extend in an indirect or somewhat curved manner between the front and rear walls 14 and 15 and the upper and lower comparatively narrow 65 wall webs of the exhaust conduits and preferably to one side of the vertical median line of the conduits, as more clearly shown in Figure 2, thus compensating for differences in expansion and contraction between the conduits and the walls of 70 the main structure or casting. It was found necessary in practice to provide some sort of support for the exhaust passages which at the same time would be of a yielding nature and would not transmit the strains and stresses to the front and 75 back walls of the casting. It is advisable, there-

fore, to provide this connection or tie at the upper and lower narrow walls of the exhaust passages (where, in practice, it has been found difficult to maintain a core sand wall), namely an ogee or indirect tie, as for example shown at 25, 5 which will flex or yield indirectly or laterally without transmitting the expanding and contracting movements of the exhaust conduits to the rest of the casting which is not subject to the expansion and contraction; it being apparent from the off-set or indirect tie construction shown in Figure 2 that the webs will permit and absorb the expanding and contracting movements of the exhaust passages.

My invention also provides a structure wherein 15 the cylinder portions are more securely tied together and a better attachment to the main structure provided without adding any difficulties in the casting thereof.

This new method or design of attaching the 20 cylinder portions to the main body of the structure consists of a grid construction of interlocking or connected ribs, as shown at 26 extending lengthwise of the casting, from one cylinder 11 to the other cylinder and integrally connected 25 at the ends therewith; this rib in turn being formed integral with the vertical inner walls 16; the ribs being formed with openings therethrough as shown at 27, see Figure 3. This rib 26 is disposed in vertically spaced relation with 30 the bottom wall 13, to which the rib 26 is connected by means of a series of laterally spaced vertically disposed ribs 28, and by the inner walls 16; the rib 26 in turn having the pedestal portion 24 secured thereto which in turn is tied to or 35 integral with the discharge ends 21 of the oppositely disposed conduits.

As is apparent, this grid formation of ribs provides a firm, rigid tie between the upper portions of the two cylinders 11, 11, namely at a 40 distance above the lower wall 13 which is also integral with the sides of the cylinders; while the lower portions of the cylinders are braced and tied to the bottom wall by means of the angular webs 29, 29; these interconnected ribs 45 providing a truss formation between the cylinders.

The exemplification of the invention is believed to be the best embodiment thereof, and the terms herein have been employed merely as terms of description and not as terms of limitation as 50 structural modifications are possible without departing from the spirit of my invention.

What I claim is:—

1. A cylinder structure comprising a single piece skeleton casting formed to provide front 55 and rear walls, a valve chamber and a cylinder at opposite ends of the casting, the cylinders being integrally united by a grid of interlocking ribs; the front and rear walls having enlarged openings; and exhaust steam conduits integrally connected to opposite ends of each valve chamber and disposed through said openings and uniting within the structure, said conduits at their sides being free of the casting and having an integral laterally expansible web connection both at top 60 and bottom with the outer walls of the structure.

2. In a locomotive cylinder construction comprising a skeleton casting formed to provide an integral valve chamber and cylinder and having top, bottom, front and back walls, the front and back walls being formed with enlarged openings, exhaust steam conduits formed integral with opposite ends of the valve chamber and extending through said openings, and integral laterally expansible web connections between the top and 70 75

the bottoms of the conduits and the front and rear walls arranged to permit independent expansion and contraction of the conduits, said web connections being the only connections between 5 said conduits and the front and rear walls.

3. A cylinder construction comprising a skeleton casting formed to provide an integral valve chamber, a cylinder, and exhaust steam conduits at opposite ends of the valve chambers, the front 10 and rear walls of the casting having openings through which the exhaust conduits extend so as to be disposed within the structure, the conduits being connected at the tops and bottoms, at one side of the vertical median line, to said 15 walls of the casting by off-set webs whereby independent expansion and contraction of the conduits relative to the front and rear walls of the casting is permitted.

4. A cylinder construction comprising a skeleton 20 ton casting formed to provide an integral valve chamber, a cylinder, and exhaust steam conduits at opposite ends of the valve chamber, the front and rear walls of the casting having openings through which the exhaust conduits extend 25 to be disposed within the structure and without contacting said front and rear walls except at the top and bottom of the conduits by means of laterally expansible web connections which permit independent expansion and contraction of 30 the conduits relative to the front and rear walls of the casting.

5. A cylinder construction comprising a skeleton casting formed to provide an integral valve chamber; a cylinder; front and rear walls provided with enlarged openings adjacent to the 35 ends of the valve chamber; exhaust steam con-

duits at opposite ends of the valve chamber and of smaller dimensions than the dimensions of said openings to permit the conduits to extend through said openings and have independent expansion and contraction; and web connections 5 diametrically spaced apart between the conduits and the front and rear walls for supporting the conduits in place.

6. A cylinder construction comprising a skeleton casting formed to provide an integral valve 10 chamber, a cylinder and front and rear walls, the front and rear walls adjacent the ends of the valve chamber being provided with enlarged openings; exhaust steam conduits integral with opposite ends of the valve chamber and disposed 15 through said openings substantially free of the walls about said openings; and conduit supporting webs between spaced apart points on the conduits and the front and rear walls of the casting.

7. A cylinder construction comprising a skeleton casting formed to provide an integral valve chamber, a cylinder, and exhaust steam conduits at opposite ends of the valve chamber, the front and rear walls of the casting having openings through which the exhaust conduits are disposed 25 so as to be substantially free of the walls about the openings, and expansible connections between each conduit and the respective wall of the cylinder casting, through which the conduit extends, and arranged to permit independent ex- 30 pansion and contraction of said conduits relative to said front and rear walls, said connections being spaced apart and being the only connections between the conduits and the front and rear walls of the casting. 35
